United States Patent

Des. 236,249

Patented Aug. 12, 1975

236,249

LUGGAGE HANDLE

Edward M. Stolarz, Yorktown Heights, N.Y., assignor to Airway Industries, Inc., West Pittsburgh, Pa.

Filed Jan. 9, 1974, Ser. No. 431,891

Term of patent 3½ years

Int. Cl. D8—06

U.S. Cl. D8—154

FIG. 1 is a top plan view of a luggage handle showing my new design;

FIG. 2 is a side elevational view;

FIG. 3 is an end elevational view; and

FIG. 4 is a sectional view taken on the line 4—4 of FIG. 2.

I claim:

The ornamental design for a luggage handle, as shown.
